Attorney

UNITED STATES PATENT OFFICE.

DANIEL B. WOOD, OF BARDSTOWN, KENTUCKY.

BLOTTER-HOLDER.

1,178,830.

Specification of Letters Patent. Patented Apr. 11, 1916.

Application filed June 12, 1915. Serial No. 33,841.

To all whom it may concern:

Be it known that I, DANIEL B. WOOD, a citizen of the United States, residing at Bardstown, in the county of Nelson and 5 State of Kentucky, have invented certain new and useful Improvements in Blotter-Holders, of which the following is a specification, reference being had to the accompanying drawings.

10 This invention relates to certain improvements in blotter holders and it is an object of my invention to provide a device of this general character having novel and improved means whereby the blotter is normally maintained at a predetermined location.

15 It is also an object of my invention to provide a device of this general character including a holder provided with novel and improved means whereby a blotter may be effectively clamped thereto.

20 The invention consists in the details of construction and in the combination and arrangement of the several parts of my improved blotter holder whereby certain important advantages are attained and the device is rendered simpler, less expensive and otherwise more convenient and advantageous for use, all as will be hereinafter more 25 fully set forth.

30 The novel features of the invention will be carefully defined in the appended claim.

35 In order that my invention may be the better understood, I will now proceed to describe the same with reference to the accompanying drawings, wherein—

40 Figure 1 is a view in perspective illustrating a blotter holder constructed in accordance with an embodiment of my invention; Fig. 2 is a view, partly in bottom plan and partly in section, of my device as herein embodied; and Fig. 3 is a side elevational view of my invention as herein disclosed, the flexible member being shown in fragment.

45 As disclosed in the accompanying drawings, 1 denotes a body or holder of predetermined configuration having secured to one face thereof a cylindrical casing 2 having rotatably supported at substantially the 50 axial center thereof the spring roller 3, rotatable about an axis perpendicular to the adjacent face of the body 1 and having secured thereto an extremity of a flexible

member 6 adapted to be wound there-around and extending through the slot 5 produced in the casing and terminating in a securing member 4, herein disclosed as a metallic ring. The securing member 4 is adapted to be connected at a suitable point upon a desk or other support, and it will be 60 at once appreciated that the spring roller 3 will serve to normally maintain the holder in close proximity to said point of attachment. However, when it is desired to employ the device it is only necessary to take 65 hold of the body or holder 1 and move the same to the place required and during this movement the spring roller 3 is placed under such tension as to automatically return the body or holder 1 to its normal position 70 when released.

The face of the body or member 1 is provided with a clamp 7 whereby a blotter B or the like may be readily clamped to the holder or body 1, and, as herein embodied, 75 such clamp comprises a substantially U-shape member formed preferably of wire of requisite gage, the stems 8 of which being free of the body or base 1 and having their ends adjacent the base of the clamping member 70 coiled, as at 9, whereby the efficiency of the clamp will be materially increased.

The marginal portion of the body 1 with which the stems 8 coat is disposed on an angle of substantially 45° and the stems 8 are correspondingly bent. By this arrangement the blotter B may be effectively employed with a possibility of breaking the same substantially entirely eliminated. The inclined margin of the body 1 is disposed 90 in a direction away from the side of the body with which the casing 2 is secured.

From the foregoing description, it is thought to be obvious that a blotter holder constructed in accordance with my invention is of an extremely simple and comparatively inexpensive nature and is particularly well adapted for use by reason of the convenience and facility with which it may be assembled, and it will also be obvious 100 that my invention is susceptible of some change and modification without material departure from the principles and spirit thereof and for this reason I do not wish to be understood as limiting myself to the precise arrangement and formation of the sev- 105

eral parts herein shown in carrying out my invention in practice.

I claim:

A blotter holder comprising a body, a spring roller carried thereby and rotatable about an axis substantially perpendicular to the adjacent face of the body, the margin of the body being inclined in a direction away from the roller, and clamping means

carried by the body overlying the inclined margin thereof.

In testimony whereof I hereunto affix my signature in the presence of two witnesses.

DANIEL B. WOOD.

Witnesses:

MORGAN YEWELL,
C. T. ATKINSON.
